UNITED STATES PATENT OFFICE.

FRANZ LIMPER, OF RECKLINGHAUSEN, GERMANY.

WICK FOR LAMPS.

SPECIFICATION forming part of Letters Patent No. 738,210, dated September 8, 1903.

Application filed August 2, 1902. Serial No. 118,104. (No model.)

To all whom it may concern:

Be it known that I, FRANZ LIMPER, a citizen of the German Empire, and a resident of Recklinghausen, Westphalia, Germany, have 5 invented certain new and useful Improvements in Wicks for Lamps, of which the following is a specification.

My invention relates to an improved wick for lamps, which consists of longitudinal 10 threads or fibers held in their proper position in the ordinary way by means of an adhesive substance.

In the accompanying drawings, Figure 1 is a side view, partly broken away, of my improved wick; and Fig. 2 is a cross-section on line A B, Fig. 1.

The special feature of the new wick is that not only the fibers *a a* are used in the manufacture of the wick, but that they are connected with each other by a kind of filter-paper or absorbing cellulose-pulp as used for the manufacture of paper, and which thus constitutes an intermediate absorbing-core *b*. As is the case with ordinary wicks composed 20 of lengthy threads, the absorbing fibers are lying lengthwise close to each other and are arranged on both sides of the absorbing-paper or cellulose-pulp, to which they are fastened by means of a proper adhesive substance. 25 Owing to this arrangement, the liquid is not only enabled to rise within the fibers without hindrance, but the layer of the absorbing-paper or cellulose-pulp substantially promotes the absorbing ability of the wick. The 30 oil rises in the paper or cellulose pulp at an advanced speed, and consequently the wick, even when it is quite new, can be lighted

almost instantaneously when put in touch with the oil. In order to provide a secure holdfast of the fibers and to keep them secure 40 in their position, it is advisable to make the paper or cellulose pulp corrugated, so that each fiber or thread lies within a groove. The fibers are thus arranged on both sides in regular position to each other, and the fibers 45 on one side of the paper will always fill the space between those on the other side. It will prove of advantage to perforate the absorbing-paper or cellulose-pulp, as at *c*, in such a way that the cotton threads or fibers 50 on both sides come occasionally in direct touch with each other. Round wicks are made by fastening together the lateral edges of the paper.

What I claim as my invention, and desire 55 to protect by Letters Patent, is—

1. A wick composed of an absorbing corrugated core, and longitudinal fibers secured within the grooves of said core, substantially 60 as specified.

2. A wick composed of an absorbing perforated core, and longitudinal fibers secured to the sides of said core, substantially as specified.

3. A wick composed of an absorbing perforated corrugated core, and longitudinal fibers secured within the grooves of said core, 65 substantially as specified.

Signed by me at Düsseldorf, Germany, this 18th day of July, 1902.

FRANZ LIMPER.
